UNITED STATES PATENT OFFICE.

FOSTER M. SPURR, OF BOSTON, MASSACHUSETTS.

ENVELOP HOLDER AND FEEDER.

1,135,067.

Specification of Letters Patent. Patented Apr. 13, 1915.

Application filed January 10, 1914. Serial No. 811,367.

To all whom it may concern:

Be it known that I, FOSTER M. SPURR, a citizen of the United States, residing at Boston, in the county of Suffolk and State 5 of Massachusetts, have invented new and useful Improvements in Envelop Holders and Feeders, of which the following is a specification.

The invention relates to and has for an 10 object to provide an improved feeding mechanism for delivering articles, such as envelopes, or the like, one at a time from the bottom of a pile of such articles.

The invention is intended primarily for 15 use in connection with an address printing machine and while being more particularly adapted for such use, its operation is not restricted in this connection, and it may be operated as an individual mechanism, 20 or in connection with any other mechanism requiring to be fed with such articles one at a time.

The invention comprises primarily a main supporting frame mounted upon suitable 25 supports or standards, a separating mechanism secured upon and medially of the main supporting frame, a delivery mechanism coactive with the separating mechanism, a hopper pivotally mounted upon 30 standards rising from the main supporting frame and adapted to over-lie the separating and delivery mechanisms, the hopper being constructed in a manner to permit its 35 adjustment for the reception of articles of various sizes, and a hopper operating mechanism coactive with the separating and delivery mechanisms.

The invention consists in the novel features hereinafter described, reference being had to the accompanying drawings which illustrate the embodiment of the invention and said invention is fully disclosed in the following description and claims.

Similar numerals of reference indicate corresponding parts in the figures of the drawings, and in which drawings:

Figure 1 is a side elevation of the improved machine. Fig. 2 is a vertical section on the line 3-3 of Fig. 3. Fig. 3 is a top plan view of the machine with the hopper removed. Fig. 4 is a vertical section on the line 4-4 of Fig. 3 showing the

operating mechanism from the side opposite to that of Fig. 2. Fig. 5 is a detail view of 55 the operating mechanism with the article in position to be delivered from the bottom of a pile of such articles supported within the hopper. Fig. 6 is a detail view of the delivery mechanism in its operative position. 60

Referring to the drawings, the main supporting frame comprises the two side-bars 1 and 2 which are suitably secured with respect to each other by means of the cross-bars 3 and 4 and are mounted upon suitable 65 standards 5 which, in the present instance, consist of substantially inverted U-shaped members having their extremities bent outwardly in opposite directions to provide the securing ears 6.

Depending from the side-bar 1 is the bearing plate 7 in which are journaled the forward ends of the drive shaft 8 and the counter-shaft 9, the inner ends of which shafts are also journaled in the bearing- 70 plates 10 and 11 respectively. The latter plates are dependently secured to the supporting bar 12 of the separating and delivery mechanisms which will hereinafter be more fully described. 75

The supporting bar 12 is secured upon the cross-bars 3 and 4 at a point medially thereof with respect to the side-bars 1 and 2 and is of a length to permit its ends to project beyond the outer edges of the cross-bars. 80

Secured to the opposite side-faces of the supporting bar 12 are the vertically disposed plates 13 between the upper portions of which is pivoted the arm 14 upon which is secured the plate 15 adapted to receive the 90 cushioning pad 16, the purpose of which pad will be hereinafter fully set forth. A link 17 is pivotally connected to the arm 14 at a point intermediate of the ends of the latter and to the link 18 and the forward end of the push-bar 19, the link 18 being also pivoted to the supporting bar 12, thus forming a toggle connection between the arm 14 and the supporting bar 12 whereby the cushioning pad 16 may be 100 raised or lowered from and to its normally inclined position as the case may be.

Secured upon the inner end of the drive shaft 8 is the spur gear 20 which meshes with the larger spur gear 21 carried upon 105 the inner end of the counter-shaft 9, the

latter gear 21 is provided upon its inner face with the crank-arm 22 pivotally connecting at its outer end with one end of the pitman 23 which is, at its opposite end, connected to the lower end of the vertically disposed oscillating bar or lever 24 which is pivotally supported at a point removed from its upper end to the vertically disposed plates 25 secured in parallel relation upon the opposite faces of the supporting bar 12. A pitman-rod 26 is pivotally connected at its rear end to the upper end of the oscillating bar or lever 24 and at its forward end to the reciprocating bar 27 which is arranged in parallel relation with respect to the supporting bar 12.

Located medially between and in parallel relation to the supporting bar 12 and the reciprocating bar 27 is a reciprocating bar 28 which is supported between the bearing-blocks 29 and 30 which are arranged between the vertically disposed plates 31 and 32 and the bearing-blocks 33 and 34 secured between the inner face of the bearing plate 10 and the oppositely arranged plate 32^a. The bearing blocks 29 and 33 also serve to support upon their upper faces the reciprocating bar 27.

Pivoted supported by the forward end 30 of the reciprocating bar 28 is the arm 35 provided at its upper end with the flap-engaging blade 36 having its front edge formed to provide the upturned lip 37. Intermediate its ends the arm 35 is provided 35 with the abutment screw 38 against which the reciprocating bar 27 is adapted to contact. The push-bar 19 which is pivotally connected to the links 17 and 18 of the toggle connection between the supporting bar 12 and the arm 14 has its rear end bent at right angles to provide the abutment 39, which is adapted to slidably rest upon the member 40 provided with the upturned portion 41 which is adapted to contact with the abutment 39 of the push-rod 19 whereby to 45 operate the toggle links 17 and 18 in raising and lowering the arm 14.

Centrally pivoted to the reciprocating bar 28 at a point intermediate its ends is the 50 oscillating member 42 having its lower end provided with the recess 43 adapted to engage with the screw 44 secured in the bearing plate 11 and its upper end provided with the cam-shaped edges 45 and 46 against 55 which the abutment screws 47 and 48, carried by the reciprocating bar 27, are adapted to contact.

Depending from the side-bars 1 and 2 of the main supporting frame and spaced from 60 the front ends thereof are the brackets 49 supporting from their lower ends the shaft 50 of the delivery mechanism.

Secured at opposite ends of the shaft 50 and curving upwardly and rearwardly 65 therefrom are the arms 51 to which is se-

cured, at their upper ends, the flap-engaging delivery blade 52.

Mounted upon the shaft 50 and projecting therefrom at right angles with respect to the curved arms 51 is the lever 53 which is pivotally connected to the bar 54 which is fixedly secured to the sliding bar 55 carried by the bearings 56 and 57 secured to the cross-bars 3 and 4 respectively.

Depending from the sliding bar 55 is the lug 58 which is adapted to be contacted with by the pivot pin 59 carried by the spur gear 21.

A spring 60 is fastened at one end to the curved arm 51 and at the other end to the depending portion of the stop member 61 secured to the cross-bar 4. A second stop-member 62 is arranged at the opposite end of the cross-bar 4 and against these stop-members the curved arms 51 are adapted to rest in their inoperative position.

Rising from the cross-bar 4 and spacedly secured thereon are the standards 63 having journaled in their upper ends the hopper supporting shaft 64 which is of a length to allow its opposite ends to project therebeyond in a manner to engage with the bearing-aperatures 65 of the depending members 66 of the substantially inverted U-shaped member 67.

Secured to the lower ends of the depending members 66 and at right angles thereto are the hopper side-bars 68 which are of a length equal to that of the side-bars 1 and 2 of the main supporting frame. The front ends of the hopper side-bars 68 are secured intermediate of the ends of the vertically disposed bars 69 which are secured with respect to each other by the cross-bars 70, the bars 69 normally resting upon the cross-bar 3 of the main supporting frame thereby supporting the hopper side-bars 68 in parallel relation with respect to the side-bars 1 and 2.

Secured to the outer faces of the vertically disposed bars 69 is the hopper plate 71 which is of a width to permit its lower edge to aline with the lower edges of the side-bars 68.

Slidably mounted upon the side-bars 68 are the guide blocks 72 connected with respect to each other by means of the cross-bar 73 to which are spacedly secured the standards 74 which support the inner hopper plate 75 corresponding in size to the face plate 71. The lower edges of the hopper plates 71 and 75 are bent inwardly toward each other to provide the article-supporting flanges 76.

Depending below the main supporting frame and in alinement with the supporting bar 12 is the substantially U-shaped yoke 77 having its vertical members 78 bent outwardly in opposite directions to provide the arms 79 and 80, the latter of said arms be-

ing slidably supported upon the drive shaft 8 and between the bearing plate 10 and the spur gear 20.

5 A bar 81 is secured at its rear end to the arm 79 and projects forwardly therefrom to a point slightly beyond the forward end of the supporting bar 12 and is secured at this point to the lower member of the bar 82, the upper member of which bar 82 is 10 projected backwardly between the plates 13 and slidably engages with the upper edge of the supporting bar 12.

15 Secured upon the backwardly projecting member of the bar 82 is the cam block 83, the cam surface of which block 83 is adapted to engage with the lower cross-bar 70 connecting the lower ends of the vertically disposed bars 69.

20 Secured upon the outer face of the large spur gear 21 is the cam member 84 having its cam surface arranged adjacent the periphery thereof and at a point substantially 120 degrees removed from the pivot pin 59 projecting from the crank-arm 22 upon the 25 opposite face of the gear 21. The U-shaped yoke 77 is positioned adjacent the spur gear 21 and parallel thereto and in a manner to permit its vertical members 78 to be alternately contacted by the cam member whereby to impart thereto a forward or rearward movement as the case may require.

The operation of the various mechanisms is as follows:—After the inner hopper plate 75 has been adjusted by sliding the guide blocks 72 along the side bars 68 to a point desirable for the placing of the required size of articles upon the supporting flanges 76 of the hopper plates 71 and 75, the articles being stacked upon the flanges 76 with 30 their flaps downward and toward the forward part of the hopper, power is applied to the drive shaft 8 which drives the counter-shaft 9 through the intermeshing gears 20 and 21 and a forward motion is imparted 35 to the reciprocating bar 27 through the pitman 23, the oscillating lever 24, and the pitman 25. As the reciprocating bar 27 moves forward the abutment screw 48 engages with the cam surface 46 of the oscillating 40 member 42 which imparts a similar forward motion to the reciprocating bar 28 which moves forward in advance of the reciprocating bar 27 and carries with it the arm 35 upon which is secured the flap-engaging 45 blade 36, until the limit of its movement is reached and the upturned portion 41 of the member 40 has engaged with the abutment 50 39 of the push-rod 19 in a manner to operate the toggle links 17 and 18 thereby 55 raising the cushioning pad 16 from its normally inclined position to a substantially horizontal position. At the same time the reciprocating bar 27 engages with the abutment screw 38 and forces it from its normally 60 65 backwardly inclined position into a

vertical position and the blade 36 into engagement with the flap of the undermost article thereby exerting a downward pulling movement upon the cushioning pad 16, the flap being held tightly between the blade 70 36 and the cushioning pad 16 and by reason of the frictional engagement with the latter.

The cam member 84 now engages with the forward vertical member of the yoke 77 and forces it forward so that the cam block 83 75 engages with the lower cross-bar 70 of the hopper and raises it up in a manner to cause the front edge of the article to disengage with the flange 76 of the hopper plate 71, after which the pivot pin 59 contacts with 80 the depending lug 58 and imparts a forward movement to the sliding bar 55 and the bar 54 and by reason of the latter's pivot connection with the lever 53 carried by the shaft 50, a rotary movement is given the 85 shaft 50 which carries the delivery blade 52 to and into engagement with the flap of the article to be delivered. The reciprocating bar 27 and the bar 28 having now reached the limit of their forward movement, are 90 returned to their normal position upon further movement of the spur gear 21, through the abutment screw 47 striking the cam edge 45 of the oscillating bar 42 swinging said bar backward. The arm 35 carrying the 95 blade 36 tilts to its normally inclined position and imparts a backward motion to the push-rod 19 and to the links 17 and 18 of the toggle connection thereby lowering the arm 14, upon which the cushioning pad 16 100 is supported, to its normally inclined position. During this retrograde movement, further motion is imparted to the delivery blade 52, which, having engaged with the flap of the article, forces the latter out of 105 engagement with the flange 76 of the hopper plate 75 and delivers same to the front of the machine. The cam member 84, carried by the gear 21, contacts with the rear vertical member of the yoke 77 and forces it 110 backward thereby causing the cam-block 83 to disengage from the lower cross-bar 70 thereby lowering the hopper into its normal position.

The usual follower plate 85 is employed 115 to properly retain the articles firmly upon the supporting flanges 76 of the hopper plates 71 and 75.

From the foregoing, it will be apparent that I have produced a new and novel construction of a machine for feeding envelops, or the like, which embodies the features of advantage enumerated as desirable in the statement of invention and the above description and while I have in the present 120 instance shown and described the preferred embodiment thereof which has been found in practice to give satisfactory and reliable results, it will be obvious that various changes may be made therein without de- 130

parting from the spirit and scope of my invention or sacrificing any of its advantages.

Having thus described my invention, what I claim as new and desire to secure by Letters Patent, is:—

1. A machine of the character described comprising a supporting frame, a hopper pivotally mounted above the supporting frame for holding a stack of envelopes, means 10 for engaging the flap of the undermost envelop of the stack retained within the hopper, means for moving the hopper to release therefrom the flap end of the envelop, means for releasing the flap from said flap-engaging means, and a second flap engaging means for delivering the envelop from the bottom of the hopper.

2. A machine of the character described comprising a supporting frame, standards 20 rising from the rear portion of said frame, a hopper pivotally supported at one edge of said standards and overlying the supporting frame and adapted to contain a stack of envelopes, means for engaging the flap of the 25 undermost envelop of said stack, means for raising said hopper to release therefrom the flap end of the envelop, means for releasing the flap from said flap-engaging means, and a second flap-engaging means for delivering 30 the envelop from the bottom of the hopper.

3. A machine of the character described comprising a supporting frame, oppositely disposed standards rising from the rear portion of the supporting frame, an adjustable 35 hopper pivotally supported at one edge from the standards and overlying the supporting frame, means for engaging the flap of the undermost envelop of a stack of envelopes retained within the hopper, means for raising 40 the forward edge of the hopper out of engagement with the front edge of the envelop, a second flap-engaging means for delivering the envelop from the bottom of the hopper, and connecting means for operating 45 the flap-engaging means, the hopper raising means and the second flap-engaging means, in one continuous movement.

4. A machine of the character described comprising a supporting frame, oppositely disposed standards rising from the rear portion of said frame, a shaft journaled on 50 the upper ends of the standards, a hopper for holding a stack of envelopes dependingly supported at one edge from the projecting ends of said shaft and overlying the supporting frame, means for engaging the flap of the undermost envelop of said stack of envelopes, means for raising said hopper to release therefrom the flap end of the undermost envelop, means for releasing the flap from said flap-engaging means, and a second flap-engaging means for delivering the envelop from the bottom of the hopper.

5. A machine of the character described comprising a supporting frame, standards 65

rising from the rear portion of the supporting frame, a shaft journaled in the upper ends of the standards, an adjustable hopper dependingly supported from the projecting ends of the shaft and overlying the supporting frame, means for engaging the flap of the undermost envelop of a stack of envelopes retained within the hopper, a cushioning pad coöoperative with the flap-engaging means, means for raising the hopper out of engagement with the front edge of the envelop, a second flap-engaging means for delivering the envelop from the bottom of the hopper, and connecting means for operating the flap-engaging means, the cushioning pad, the hopper raising means, and the second flap-engaging means, in one continuous movement.

6. A machine of the character described comprising a pair of standards, a supporting frame secured thereon, standards rising from the rear portion of the supporting frame, a shaft journaled in the upper ends of the standards, an inverted U-shaped member supported from the projecting ends of the shaft, a hopper supported from the extremities of the U-shaped member and overlying the supporting frame, means for engaging the flap of the undermost envelop of a stack of envelopes retained within the hopper, a cushioning pad coöoperative with the flap-engaging means, means for raising the hopper out of engagement with the front edge of the envelop, a second flap-engaging means for delivering the envelop from the bottom of the hopper, and connecting means for operating the flap-engaging means, the cushioning pad, the hopper raising means, and the second flap-engaging means, in one continuous movement.

7. A machine of the character described comprising a pair of standards, a supporting frame secured thereon, standards rising from the rear portion of the supporting frame, a shaft journaled in the upper ends of the standards, an inverted U-shaped member supported from the projecting ends of the shaft, a hopper supported from the extremities of the U-shaped member and overlying the supporting frame, a blade for engagement with the flap of the undermost envelop of a stack of envelopes retained within the hopper, a cushioning pad coöoperative with the blade, means for raising the hopper out of engagement with the front edge of the envelop, a flap-engaging means for delivering the envelop from the bottom of the hopper, and connecting means for operating the blade, the cushioning pad, the hopper raising means, and the flap-engaging delivery means, in one continuous movement.

8. A machine of the character described comprising a pair of standards, a supporting frame secured thereon, standards rising from the rear portion of the supporting

frame, a shaft journaled in the upper ends of the last mentioned standards, an inverted U-shaped member supported from the projecting ends of the shaft, a hopper supported from the extremities of the U-shaped member and overlying the supporting frame, a blade for engagement with the flap of the undermost envelop of a stack of envelops retained within the hopper, a cushioning pad coöperative with the blade, a cam-block operating to raise the hopper out of engagement with the front edge of the envelop, a flap-engaging means for delivering the envelop from the bottom of the hopper, and connecting means for operating the blade, the cushioning pad, the cam-block, and the flap-engaging delivery means, in one continuous movement.

9. A machine of the character described comprising a pair of standards, a supporting frame secured thereon, standards rising from the rear portion of the supporting frame, a shaft journaled in the upper ends of the last mentioned standards, an inverted U-shaped member supported from the projecting ends of the shaft, a hopper supported from the extremities of the U-shaped member and overlying the main frame, a blade for engagement with the flap of the undermost envelop of a stack of envelops retained within the hopper, a cushioning pad coöperative with the blade, a cam-block operating to raise the hopper out of engagement with the front edge of the envelop, a second blade adapted for engagement with the flap of the envelop whereby to deliver same from the bottom of the hopper, and connecting means for operating the first mentioned blade, the cushioning pad, the cam-block, and the delivery blade, in one continuous movement.

10. A machine of the character described comprising a pair of standards, a supporting frame secured thereon, standards rising from the rear end portion of the supporting frame, a shaft coextensive with the supporting frame and journaled in the upper ends of the last mentioned standards, an inverted U-shaped member supported from the projecting ends of the shaft, a hopper supported from the extremities of the U-shaped member and overlying the supporting frame, a blade adapted for engagement with the flap of the undermost envelop of a stack of envelops retained within the hopper, means for raising and lowering the blade into and out of engagement with the flap of the envelop, a cushioning pad coöperative with the blade, a cam-block operating to raise the hopper out of engagement with the front edge of the envelop, a second blade adapted for engagement with the flap of the envelop whereby to deliver same from the bottom of the hopper, and connecting means for operating the first mentioned blade, the cushion-

ing pad, the cam block, and the delivery blade, in one continuous movement.

11. A machine of the character described comprising a hopper adapted to support opposite edges of a stack of articles, means for gripping the undermost of said articles near one of its edges, means for raising said hopper to release therefrom the engaged edge of said article, means for releasing the gripping means from said article, and a flap engaging means for engaging the article and delivering the same from the hopper.

12. A machine of the character described comprising a hopper pivotally mounted for vertical adjustment and adapted to support the opposite edges of a stack of articles near one edge thereof, means coöperating with said gripping means for supporting said article, means for raising said hopper out of engagement with the gripped edge of the article, means for releasing said article from the gripping means, and other means for engaging the article after its release from the gripping means to deliver the same from the bottom of the hopper.

13. A machine of the character described comprising a hopper pivotally mounted for vertical movement and adapted to support the opposite edges of a stack of folded articles, means for engaging the fold of the undermost of said articles, means for supporting the underside of the fold and coöperating with the first-mentioned means, means for raising the hopper out of engagement with the folded edge of the article, means for releasing the folded edge from said engaging means, a second fold-engaging means for delivering the article from the bottom of the hopper and a series of operating devices for actuating the first engaging means, the means coöperative therewith, the hopper raising means and the delivering means in one continuous movement.

14. A machine of the character described comprising a hopper pivotally mounted for vertical movement and adapted to support the opposite edges of a stack of folded articles, a blade adapted to engage the fold of the undermost of said articles, means for supporting the underside of the fold and coöperative with the blade, means for raising the hopper out of engagement with the front edge of the article, means for releasing the article from the blade and its coöperating means, means for engaging the fold to deliver the article from the hopper after it has been released by said blade and said means coöperative therewith, and operating means for actuating the blade, the means coöperative with the blade, the hopper raising means, and the last mentioned means, in one continuous movement.

15. A machine of the character described comprising a hopper pivotally mounted for vertical movement and adapted to support the

opposite edges of a stack of folded articles, a blade adapted to engage the fold of the undermost of said articles, a cushioning pad coöperative with the blade and adapted to engage the underside of the fold, means for raising the hopper out of engagement with the front edge of the article, means for releasing the article from the blade and its co-operating means, means engaging the fold after it has been released by said blade and adapted to deliver the article from the bottom of the hopper, and operating means for actuating the blade, the cushioning pad, the hopper raising means, and the last mentioned means in one continuous movement.

16. A machine of the character described comprising a supporting frame, oppositely disposed standards rising from the rear portion of said supporting frame, an adjustable hopper pivotally supported from said standards and overlying said frame and adapted to retain the opposite edges of a stack of envelopes, means adapted to engage the flap of the undermost of said envelopes to hold same against accidental displacement from the bottom of the hopper, means for raising the forward edge in the hopper to disengage the flap end of the envelop from the

hopper, means for releasing said flap engaging means, and a second flap-engaging means to deliver the envelop from the bottom of the hopper.

17. In a machine of the character described, the combination of a pivoted hopper comprising a fixed wall and a movable wall adjustable relative to the fixed wall to accommodate folded articles of various sizes, of means adapted to engage the fold of the undermost of said articles to hold same against accidental displacement from the bottom of the hopper, means for raising the forward edge of the hopper out of engagement with the front edge of the article engaged by the first-mentioned means, means for rendering said fold-engaging means inoperative, and means engaging the fold of the article to deliver the same from the bottom of the hopper.

In testimony whereof I have hereunto set my hand in presence of two subscribing witnesses.

FOSTER M. SPURR.
